UNITED STATES PATENT OFFICE.

THOMAS J. POWERS, OF STEUBENVILLE, OHIO.

FACE-SHIELD.

1,075,667.

Specification of Letters Patent. Patented Oct. 14, 1913.

Application filed January 18, 1913. Serial No. 742,914.

To all whom it may concern:

Be it known that I, THOMAS JOSEPH POWERS, a citizen of the United States, residing at Steubenville, in the county of Jefferson and State of Ohio, have invented certain new and useful Improvements in Face-Shields, of which the following is a specification.

This invention relates to improvements in face shields and has for its object to provide an adjustable transparent shield for iron workers to prevent sparks, filings, and the like from coming into contact with the wearer's face or other portion of the head.

Another object of the invention is to provide the combination of a face shield with a self adjusting head gear for supporting the same.

With the above and other objects in view which will be more fully explained in the following specification, I have invented the device illustrated in the accompanying drawings in which—

Figure 1 is a side elevation of my device illustrating its application to the head of a wearer, Fig. 2 is a side elevation of the device showing the face shield folded upon the head gear or cap, Fig. 3 is an enlarged detail sectional view of the face shield, Fig. 4 is a rear elevational view of the device, Fig. 5 is a sectional view through the head band of a slightly modified form of the invention, Fig. 6 is a side elevation of a modified form of a cap band, Fig. 7 is a front elevation of a modified shield member and Fig. 8 is a section taken on line A—A of Fig. 7.

Like reference characters indicate like parts throughout the specification and in the several views in the drawings in which 40 1 indicates a cap consisting of a band 2 and a covering 3, said band being made preferably of metal and pivotally secured to its opposing sides are arms 4 and 5 held by screws 6. To the lower ends of the arms 45 4 and 5 is secured a face shield 7 consisting of a frame 8 which holds a transparent member 9 which is adapted to shield the wearer's face from heat, sparks, filings or any foreign material, yet which will not interfere with the vision. The arms 5 and 4 are secured to the member 8 in the same manner as they are secured to the member 2. The members 4 and 5 are made of spring steel and have their ends *a* and *b* returned 50 55 in a loop so that the screws 6 passing through said loops may be tightened to

cause sufficient friction so that said arms 4 and 5 will remain in any position in which they are set whereby the face shield may be readily adjusted to any desired position. 60 The halves (not shown) through which the screws 6 pass are sufficiently large to permit of a sliding movement of the ends *a* and *b* when said screws are tightened or loosened.

In Fig. 5 I show a slightly modified form 65 of the device in which the head band 11 is of spring steel or other spring material and the end 12 overlaps the end 13 whereby the cap will adjust itself to fit any size head. The covering 14 is provided with a loose 70 plait 15 whereby the cap will expand as well as the band. An inner band 16 between which and the band 11, the edges of the covering 14 may be held may be provided if desired. The screws 6 may be 75 tightened to increase the friction between the springs and arms.

Figs. 6, 7 and 8 illustrate another modification of the device in which the head band 17 extends only partially around the cap 80 18 (shown in section in Fig. 8) and its ends 19 and 20 are connected by a leather strap 21 the end 22 of which may be held by the buckle 23 whereby the device may be fastened securely to the head of a wearer. The 85 modification shown in these figures also contemplates a nonconducting (preferably asbestos) face shield 24 which is not necessarily transparent but which is provided with glass covered peep holes 25 and 26 90 which are arranged to oppose the wearer's eyes. The band 17 may be located on either the inner or outer side of the cap fabric or it may be interposed between the folds of the fabric as indicated in Fig. 8. 95

Having described my invention that which I claim to be new and desire to procure by Letters Patent is:

1. In a device for the purpose set forth comprising a supporting element, a pair of suspension elements, a shield, means for pivotally connecting said suspension elements respectively to the shield and supporting element, said suspension elements bent upon themselves to provide frictional grips engaging with said means for maintaining said suspension elements and shield in an adjusted position. 100

2. A device for the purpose set forth comprising a supporting element, a face shield, 110 means for pivotally connecting said suspension elements to said supporting elements,

and means for pivotally connecting said suspension elements to said shield, said suspension elements bent upon themselves to provide frictional gripping loops engaging the means for pivotally connecting said suspension elements to the shield whereby the latter is maintained in an adjusted position.

3. A device for the purpose set forth comprising a supporting element, suspension elements, means for pivotally connecting the suspension elements to the supporting element, said suspension elements having their lower ends bent upon themselves to provide loops, screws extending through said loops for pivotally connecting said loops to said shield, said loops provided with frictional gripping means engaging with the heads of the screws for maintaining the shield in the position to which it has been adjusted.
4. A device for the purpose set forth comprising a supporting element, suspension

elements, means for pivotally connecting the suspension elements to the supporting element, said suspension elements having their lower ends bent upon themselves to provide loops, screws extending through said loops for pivotally connecting said loops to said shield, said loops provided with frictional gripping means engaging with the heads of the screws for maintaining the shield in the position to which it has been adjusted, said suspension elements having their upper ends provided with means engaging with the supporting element for maintaining the suspension elements adjustable at an angle with respect to the supporting element.

In testimony whereof I affix my signature in presence of two witnesses.

THOMAS J. POWERS.
